UNITED STATES PATENT OFFICE

THOMAS G. MYERS, OF LOS ANGELES, CALIFORNIA, ASSIGNOR TO U. S. ELECTRICAL MANUFACTURING COMPANY, OF LOS ANGELES, CALIFORNIA, A CORPORATION OF CALIFORNIA

DESIGN FOR A VERTICAL ELECTRIC MOTOR

Application filed August 4, 1930. Serial No. 36,551. Term of patent 14 years.

To all whom it may concern:

Be it known that I, THOMAS G. MYERS, a citizen of the United States, and a resident of the city of Los Angeles, in the county of Los Angeles and State of California, have invented a new, original, and ornamental Design for a Vertical Electric Motor, of which the following is a specification, reference being had to the accompanying drawing, forming part thereof.

The single figure is a perspective view of a motor embodying my invention.

I claim:

The ornamental design for a vertical electric motor, substantially as shown.

In testimony whereof I have hereunto set my hand.

THOMAS G. MYERS.
